WATCH BOX PAD

Samuel Flier, Springfield, Mass.

Application June 13, 1944, Serial No. 540,047

1 Claim. (Cl. 206—75)

1

The present invention relates to pads for watch and jewelry boxes and to a method of making the same.

Pads currently used are made as follows: a piece of pasteboard is die-cut to appropriate shape and dimensions, it is then assembled, and finally covered by hand with suitable material such as velveteen.

The pad forming the subject matter of the present invention is made in the following way: a piece of pasteboard is scored or grooved in accordance with a predetermined pattern, it is covered with velveteen or other suitable material, and finally die-cut.

The new method is quicker and cheaper, saving both labor and material.

It is the object of the present invention to produce such pad and the method of making the same.

A preferred embodiment of the present invention is shown in the accompanying drawing in which—

Figure 1 is a longitudinal, vertical section of the pad, shown in assembled or folded position in a watch box, carrying a strap wrist watch;

Figure 2 is a perspective view of the pad, shown in assembled condition;

Figure 3 is a transverse section on the line 3—3 of Figure 2;

Figure 4 is a plan view of the pad in unassembled or unfolded condition; and

Figure 5 is a bottom view of the pad in unassembled or unfolded condition.

The pad 10 herein claimed is made of pasteboard or other suitable material, covered with a covering 11 of velveteen or similar material. It is made as follows:

A piece of pasteboard is scored or grooved on its under surface with spaced parallel grooves or score lines 12 as shown in Figure 5. The top surface of the pasteboard is now covered with velveteen or other suitable textile or other material. The velveteen-covered pasteboard is now die-cut to the shape shown in Figures 4 and 5, that is, to two end to end rectangular portions, the head portion 13 being larger, at least in width, than the foot portion 14. The side edges 15 of head portion 13 are spaced from and parallel to grooves 12 and are coextensive therewith. The side edges 16 of foot portion 14 are in line, respectively with said grooves. The portions between the grooves and side edges 15 comprise flaps 15a which may be bent over as hereinafter described.

As part of the die-cut process or as part of the grooving or scoring process above mentioned, the pasteboard is scored with two oppositely dis-

2

posed pairs of spaced, parallel score lines. The upper line 17a of each of these pairs of score lines coincides with the line at which head portion 13 and foot portion 14 meet. The lower line 17b is in the foot portion.

Also as part of the die-cut process, a U-shaped cut 18 is made in the foot portion, the yoke portion 19 thereof joining score lines 17a with each other, the arm portions 20 joining one of the score lines 17a with one of the score lines 17b, and the other of the score lines 17a with the other of the score lines 17b.

The pad is now ready to be folded and inserted into box 25. It is folded on groove lines 12 and score lines 17a and 17b, as shown in Figure 2. Head portion 13 becomes an elevated platform member, supported by downturned flaps 15a and by the downturned members 17c formed between score lines 17a and 17b. The tongue 18a which is formed by U cut 18 now lies underneath the platform member, on a plane with foot portion 14. The net result is a rectangular shaped aperture 21 formed between downturned members 17c.

The pad as shown in Figure 2 is now inserted into box 25 as shown in Figure 1. The watch strap 26 carrying the buckle is laid on the elevated portion, the watch proper 27 on the foot portion, and the apertured strap 28 is turned under the watch and inserted into aperture 21.

The embodiment herein described and the method of making the same are not intended to limit the invention to the specific features disclosed. Modifications both of the article and of the method are possible within the broad principles of the invention and are here contemplated.

As used in the claims hereto appended, the word "scoring" is intended to include "grooving" as well as "scoring."

I claim:

40. A jewelry pad blank having a wide and narrow portion comprising a sheet of pasteboard and a fabric covering on the top side of said pasteboard, a pair of parallel score lines in said wide portion of said pasteboard extending longitudinally thereof of adjacent its side edges to form a pair of flaps which may be folded downwardly, additional parallel score lines in said narrow portion of said pasteboard extending transversely thereof immediately adjacent said wide portion to form a step portion, and a U-shaped cut in both the pasteboard and the fabric covering thereon between the last mentioned score lines with the base of the U-shaped cut coinciding with the transverse score line nearest said wide portion to form an opening in said step portion.

SAMUEL FLIER,
